GEORGE E. GLATTHAR AND FREDERICK WENING, OF CLEVELAND, OHIO, ASSIGNEES
TO THE ART METAL COMPANY, OF CLEVELAND, OHIO, A CORPORATION OF OHIO

SHADE HOLDER

Application filed August 29, 1930. Serial No. 478,574.

This invention relates to improvements in electric lighting fixtures and more particularly, in the holders for the shades or globes thereof.

5 The general objects of the present invention are the provision of an improved shade or globe holder which is of extremely simple and inexpensive construction; in which one or more of the supporting members of the 10 holder, which members yieldingly engage the rim or neck of the shade or globe to be supported, are so constructed and arranged as to be capable of a very great number of adjustments inwardly and outwardly toward 15 and from the rim or neck of the shade or globe, so that proper support of the shade or globe is always insured; and which holder is of neat and attractive appearance due, among other things, to the location of the 20 supporting members of the holder within the canopy or housing thereof, although such of said supporting members as are adjustable having the operating part of their adjusting means conveniently but not conspicuously located outside the canopy or housing of the 25 holder.

Further and more specific objects of the invention are in part obvious and in part will appear more in detail hereinafter.

30 The invention will be readily understood from the following description thereof, reference being had to the accompanying drawings in which

Fig. 1 is a side elevation of the present 35 improved holder with a shade or globe supported thereby, a part of the lower portion of said holder being broken away to show interior construction; and Fig. 2 is a bottom plan view of said holder, a part of the lower 40 portion thereof being in cross section to more clearly illustrate the present invention.

The particular shade or globe holder shown in the drawings includes a sheet metal, generally bell-shaped canopy or housing 1, 45 within the upper portion of which are suitably arranged the usual light socket and electrical connections. Said canopy or housing is provided at its upper end with a vertically disposed, short cylindrical extension 2 having 50 a top opening (not shown) through which

extend the electric wires (also not shown). In the side wall of this extension are two diametrically opposed apertures to removably receive the inwardly bent ends 3 of an inverted, generally U-shaped holder support 55 4. The bottom portion 5 of the canopy or housing 1 is of a cylindrical shape and terminates at its lower end in an outwardly rolled annular bead 6.

Circumferentially spaced around and suitably secured to the inner surface of the bottom cylindrical portion 5 of the holder are the shade or globe supporting members thereof, three in the present instance. These supporting members are adapted to yieldingly 60 engage the rim or neck 8 of a shade or globe 9 to be supported, and may be either adjustably or nonadjustably secured to the holder canopy or housing. In the present embodiment of the invention, each of the three supporting members is riveted at 12 and therefore nonadjustably secured to the cylindrical body portion 5 of the canopy or housing, as clearly shown in the drawings. Two of the supporting members, 13 and 14, are alike, and have only the yieldability afforded by the metal of which they are made, which metal, for example, may be phosphorous bronze. The third supporting member 15, however, is of a widely different form, being highly 65 resilient and therefore capable of almost an infinite number of adjustments inwardly and outwardly toward and from the rim or neck of the shade or globe to be supported. This widely adjustable supporting member 15 provides substantially all the adjustment that is needed for the proper support of shades or globes of various sizes, so that the other supporting members, 13 and 14, may be of the 70 so-called "nonadjustable" type.

As before mentioned, supporting members 13 and 14 have, however, the yieldability afforded by the metal of which they are made, so that they yieldingly engage, to some extent, at least, the rim or neck 8 of the shade or globe 9. In the present embodiment of the invention, each of these two supporting members is in the form of a metal strip, bent 75 to provide a securing portion 17 and a supporting portion 18, the securing portion, for 80

which a little more than half the strip is used, being riveted at 12 in a vertically disposed position to the inner surface of the cylindrical bottom portion 5 of the canopy or housing 1, as clearly shown in Fig. 1. The supporting portion 18 of each of these two supporting members extends inwardly and upwardly at substantially a forty-five degree angle from the bottom of the securing portion thereof and terminates in an outwardly rolled bead 20.

The third and highly adjustable supporting member 15 includes a comparatively long, flexible strip 20 of spring metal, such as 15 spring brass, said strip being circumferentially arranged along the inner surface of the bottom portion 5 of the canopy or housing with its ends riveted at 12 thereto. This third supporting member is arranged in opposed 20 relation to supporting members 13 and 14, both of which are preferably arranged a little nearer to each other than to supporting member 15, as shown in Fig. 2.

In nonsupporting position, strip 20 lies 25 closely alongside the canopy or housing bottom portion 5, as indicated by the dotted line A, Fig. 2. To move the middle portion of this strip inwardly and outwardly into and out of supporting position, a set screw 30 22 is employed, said screw being mounted in a threaded aperture in a bushing 23 non-rotatably mounted in an opening 24 in the cylindrical bottom portion 5 of the canopy or housing, as clearly indicated in the drawings. The bushing 23 is maintained in the 35 canopy or housing opening 24 by the enlarged outer head of said bushing and the inner flange or peened-over portion 26 thereof, and non-rotation of said bushing with 40 respect to said canopy or housing opening 24 is secured by making said opening and the middle portion of said bushing of noncircular shape, such as rectangular, as shown, or by soldering said bushing in said opening, as 45 will be readily understood.

The slotted operating head 28 of the adjusting screw 22 lies outside the bushing, and hence outside the canopy or housing so that it is convenient for manipulation but 50 comparatively inconspicuous. The inner end of said screw, which may be flattened to prevent its withdrawal and possible loss, engages the outer surface of the metal strip 20. By simply turning this screw, the middle portion 55 of strip 20 may be moved inwardly any desired amount, such as to supporting positions B or C, or to any other position, as will be readily understood, the number of positions of adjustment being very great.

60 Proper support of the shade or globe is therefore always insured, by the simple and convenient adjustment of a single supporting member. Shades or globes with rims or necks of all the usual sizes may be supported 65 in the present holder, and if further adjust-

ment should be needed, for any reason, the supporting portions 18 of the supporting members 13 and 14 may be either knocked inwardly or outwardly the necessary amount, as will be readily understood.

70

What we claim is:

1. A shade or globe holder, comprising a canopy provided within the bottom portion thereof with a pair of opposed shade or globe supporting members adapted for supporting engagement with the rim or neck of the shade or globe, one of said members comprising a strip of flexibly resilient metal having its ends secured to the canopy bottom portion and also comprising an adjusting screw carried by said canopy bottom portion and having its inner end engaging the middle portion of said strip, so that by adjusting said screw, the middle portion of said strip is moved inwardly and outwardly to and from various shade or globe supporting positions.

75

2. A shade or globe holder as set forth in claim 1, characterized in that the ends of said metal strip are rigidly secured to the 80 bottom portion of the canopy.

85

3. A shade or globe holder as set forth in claim 1, characterized in that said adjusting screw is mounted in a bushing carried by 90 said canopy bottom portion.

95

4. A shade or globe holder as set forth in claim 1, characterized in that said adjusting screw is mounted in a bushing nonrotatably carried by said canopy bottom portion.

100

5. A shade or globe holder as set forth in claim 1, characterized in that said adjusting screw is mounted in a bushing arranged in an opening in the bottom portion of said canopy, said canopy opening and that part of the bushing lying within said opening 105 being of noncircular shape.

105

6. A shade or globe holder as set forth in claim 1, characterized in that said metal strip is of appreciable length so that the middle portion of said strip can be moved inwardly 110 an appreciable amount.

110

7. A shade or globe holder as set forth in claim 1, characterized in that said metal strip is of spring metal, so that it is resilient or flexible.

115

8. A shade or globe holder as set forth in claim 1, characterized in that said metal strip is made of spring brass and is of appreciable length.

120

In testimony whereof we hereby affix our signatures.

GEORGE E. GLATTHAR.
FREDERICK WENING.
